Primary Examiner — Jeffrey D Asch*(74) Attorney, Agent, or Firm* — Banner & Witcoff, Ltd(57) **CLAIM**

The ornamental design for a handset, as shown and described.

DESCRIPTION

FIG. 1 is a perspective view of a handset showing our new design;
FIG. 2 is a front view thereof;
FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a perspective view of a second embodiment of a handset showing our new design;
FIG. 9 is a front view thereof;

FIG. 10 is a rear view thereof;

FIG. 11 is a left side view thereof;

FIG. 12 is a right side view thereof;

FIG. 13 is a bottom view thereof; and,

FIG. 14 is a top view thereof.

The broken lines of the handset in FIGS. 1-7 and the unshaded regions therein are for illustrative purposes only and form no part of the claimed design.

1 Claim, 10 Drawing Sheets(56)
